PATIENT HANDLING MEANS FOR BATHTUBS

John N. Gross, San Diego, Calif.

Application April 17, 1943, Serial No. 483,492

9 Claims. (Cl. 4—185)

My invention relates to a patient handling means for bathtubs, more particularly a means for lowering patients into and elevating patients from the lower interior side of bathtubs for bathing said patients, and the objects of my invention are:

First, to provide a means of this class in which a patient supporting table is readily and easily lowered into a bathtub and submerged below the surface of water in said bathtub for bathing a patient on said patient supporting table;

Second, to provide a means of this class in which the patient supporting table is readily elevated to a position above the upper side of the bathtub for use as a massage table;

Third, to provide a means of this class in which a patient supporting table is readily elevated to a position above a bathtub for drying a patient thereon after bathing;

Fourth, to provide a means of this class in which a patient supporting table is readily and easily elevated to a considerable distance above the bathtub whereby patients may be removed therefrom substantially on a level with conventional patient carriages;

Fifth, to provide a means of this class in which a motor may be used in lowering or elevating the patient into or out of bathtubs whereby smooth uniform movement of the patient is accomplished;

Sixth, to provide a means of this class in which the operating mechanism is enclosed in a readily accessible mechanism encasing compartment in the side of the bathtub providing a smooth unobstructed sidewall of the bathtub and convenient access to the operating mechanism when desired;

Seventh, to provide a means of this class in which the operating motor is insulated from all connecting parts whereby the patients while bathing are protected from electrical shocks;

Eighth, to provide a novel patient handling means for bathtubs of this class;

Ninth, to provide a means of this class which is very safe and smooth in operation and is therefore well adapted for use in handling helpless patients; and

Tenth, to provide a means of this class which is very simple and economical of construction, efficient, durable and which will not readily deteriorate or get out of order.

With these and other objects in view as will appear hereinafter, my invention consists of certain novel features of construction, combination and arrangement of parts and portions as will

be hereinafter described in detail and particularly set forth in the appended claims, reference being had to the accompanying drawing and to the characters of reference thereon which form a part of this application in which:

Figure 1 is a side elevational view of the bathtub with which my patient handling means is connected; Fig. 2 is a transverse sectional view of the bathtub taken from the line 2—2 of Fig. 1 and showing my patient handling means in connection therewith; Fig. 3 is a longitudinal sectional view of the bathtub taken from the line 3—3 of Fig. 2 showing part of the mechanism of my patient handling means in connection with the bathtub; Fig. 4 is a longitudinal sectional view of the bathtub and my patient handling means taken from the line 4—4 of Fig. 2; Fig. 5 is an enlarged fragmentary sectional view taken from the line 5—5 of Fig. 2 and showing a portion in elevation to facilitate the illustration; Fig. 6 is an enlarged fragmentary sectional view taken from the line 6—6 of Fig. 3 showing parts and portions in elevation to facilitate the illustration, and Fig. 7 is an enlarged sectional view taken from the line 7—7 of Fig. 3.

Similar characters of reference refer to similar parts and portions throughout the several views of the drawing.

The bathtub 1, crankshafts 2 and 3, patient supporting table 4, worm gears 5 and 6, worm pinions 7 and 8, motor 9, shafts 10 and 11, insulation couplings 12 and 13, and the packing gland 14 constitute the principal parts and portions of my patient handling means for bathtubs.

The bathtub 1 is provided with sidewall portions 1a and 1b which are substantially conventional in form, as shown best in Fig. 2 of the drawing. This bathtub 1 is arranged to contain water for bathing purposes and one end of this bathtub 1 is provided with a curved portion 1c which is in conforming arcuate relation with the radius of the crankshaft 3, as shown in Fig. 4 of the drawing. Integral with the sidewall portion 1b of the bathtub is the mechanism casing portion 1d, as shown best in Fig. 2 of the drawing. Pivotally connected with the outer side of this mechanism casing portion 1d are the doors 1e and 1f. These doors 1e and 1f are supported on hinges 1g and 1h providing convenient access to the mechanism in the mechanism casing portion 1d, as shown best in Figs. 1 and 2 of the drawing.

The crankshafts 2 and 3 are substantially U-shaped in form, as shown best in Fig. 2 of the drawing. The opposite ends of these crankshafts

2 and 3 are disposed at a right angle and are journalled in the opposing sidewall portions 1a and 1b of the bathtub 1. These crankshafts 2 and 3 are identical in form therefore the opposite ends of the crankshafts 2 and 3, as shown in Figs. 5 and 6, respectively, are common to both the crankshafts 2 and 3. In Fig. 5 of the drawing the end portion 2a of the crankshaft 2 is shown journalled in the sidewall portion 1a of the bathtub 1. The journal portion 1a of the sidewall portion 1a is enclosed at the end 2a of the crankshaft 2 whereby leakage of water from the bathtub 1 around the end portion 2a of the crankshaft 2 is eliminated.

In Fig. 6 of the drawing the end portion 3a of the crankshaft 3 is shown journalled in the sidewall portion 1b of the bathtub 1. This end portion 3a of the crankshaft 3 extends through the sidewall portion 1b of the bathtub 1 and is provided with a packing gland 14 thereon arranged to prevent leakage of water from the interior of the bathtub 1 outwardly around the end 3a of the crankshaft 3.

Rigidly connected with the end portion 3a of the crankshaft 3 is the worm gear 6, all as shown best in Fig. 6 of the drawing.

In connection with the end portion 2b of the crankshaft 2 is the worm gear 5, as shown best in Figs. 2 and 3 of the drawing.

Journalled on the crankshafts 2 and 3 is the patient supporting table 4. Connected with this patient supporting table 4 at its opposite ends are bearing members 4a and 4b which are journalled on the crankshafts 3 and 2, respectively, as shown best in Figs. 2 and 4 of the drawing. This patient supporting table 4 is a relatively rigid member arranged to support patients in connection with the crankshafts 2 and 3.

The motor 9 is supported on a bracket 9a which is provided with an insulation block 9b, as shown best in Figs. 2 and 3 of the drawing. Connected with opposite ends of the shaft of the motor 9 are the insulation couplings 12 and 13. These insulation couplings 12 and 13 are substantially conventional couplings and are provided with intermediate coupling portions 12a and 13a which are formed of insulation material, as shown in Fig. 7 of the drawing. This insulation material is a non-conductor of electricity and the block 9b is likewise a non-conductor of electricity thus completely insulating the motor 9 from its connecting mechanism and the bathtub 1.

The shaft 11 is journalled in the bracket 11a and is connected with the insulation coupling 12. The shaft 10 is journalled in the bracket 10a and is connected with the insulation coupling 13. Rigidly connected with the ends of the shafts 10 and 11 are the worm pinions 8 and 7 respectively. These worm pinions 7 and 8 mesh with the worm gears 5 and 6 in connection with the crankshafts 2 and 3, as hereinbefore described.

The operation of my patient handling means for bathtubs is substantially as follows:

When it is desired to bathe a helpless patient the motor 9 is operated in the desired direction for elevating the patient supporting table 4 to substantially the dashline position, as shown in Fig. 2 of the drawing. The patient is placed upon the patient supporting table 4 and the motor 9 is then operated in the reverse direction, it being noted that this motor 9 is a reversible electric motor, and is a relatively slow motor arranged to slowly elevate and lower the patient supporting table from and into the bathtub 1.

When the patient is positioned upon the patient

supporting table the patient is slowly lowered into the bathtub 1 by revoluble operation of the motor 9 which revolves the worm pinions 7 and 8 in connection with the worm gears 5 and 6 which slowly revolve the crankshafts 2 and 3. When the crankshafts 2 and 3 have revolved to the position as shown by solid lines in Fig. 4 of the drawing, the motor is stopped and the patient supporting table 4 is submerged in the water in the bathtub and the patient on the patient supporting table may be bathed as desired.

After bathing the patient the patient supporting table 4 is raised to the dashline position as shown in Figs. 2 and 4 of the drawing, whereupon the patient is dried and may be massaged upon the patient supporting table.

It will be noted that the uppermost dashline position of this patient supporting table 4, as shown in Figs. 2 and 4 of the drawing, is a considerable distance above the bathtub 1 whereby patients may be removed therefrom and positioned on a patient carriage which is normally on the same plane with said patient supporting table 4 when in the dashline position as shown in Figs. 2 and 4 of the drawing.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a patient handling means for bathtubs of the class described, the combination with a bathtub of two U-shaped crankshafts journalled at opposite sides in the side walls of said bathtub and a patient supporting table provided with stationary bearing portions near its opposite ends journalled on said crankshafts said table shiftable longitudinally and vertically between the side walls of said bathtub.

2. In a patient handling means for bathtubs of the class described, the combination with a bathtub of two U-shaped crankshafts journalled at opposite sides in the side walls of said bathtub, a patient supporting table provided with stationary bearing portions near its opposite ends journalled on said crankshafts said table shiftable longitudinally and vertically between the side walls of said bathtub and means for revolving said crankshafts.

3. In a patient handling means for bathtubs of the class described, the combination with a bathtub of two U-shaped crankshafts journalled at opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts and worm pinions in mesh with said worm gears.

4. In a patient handling means for bathtubs of the class described, the combination with a bathtub of two U-shaped crankshafts journalled at opposite sides in the side walls of said bathtub, a patient supporting table provided with bearing portions near its opposite ends journalled on said crankshafts said table shiftable longitudinally and vertically between the side walls of said

bathtub and means for revolving said crankshafts including worm gears on the end of said crankshafts, worm pinions in mesh with said worm gears, and a motor for revolving said worm pinions.

5. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

6. In a patient handling means for bathtubs of the class described, the combination with a bathtub of two U-shaped crankshafts journalled in the opposite side walls of said bathtub, a patient supporting table provided with bearing portions near its opposite ends journalled on said crankshafts said table shiftable longitudinally and vertically between the side walls of said bathtub, and packing gland means in connection with the side wall of said bathtub engaging the outer sides of said crankshafts.

7. In a patient handling means for bathtubs of the class described, the combination of a bathtub

having an enclosed compartment portion within one side wall, crankshafts having their ends journalled in the side walls of said bathtub and one end extending into said compartment, and a patient supporting table journalled on said crankshafts intermediate their ends, said table shiftable both longitudinally and vertically between the side walls of said bathtub.

5. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

8. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

10. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

15. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

20. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

25. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts including worm gears on the end of said crankshafts, worm pinions in mesh with said worm gears, a motor for revolving said worm pinions, and insulation means interposed between said motor and said worm pinions.

30. In a patient handling means for bathtubs of the class described, the combination with a bathtub of two U-shaped crankshafts journalled in opposite sides in the side walls of said bathtub, a patient supporting table provided with bearing portions near its opposite ends journalled on said crankshafts said table shiftable longitudinally and vertically between the side walls of said bathtub and means for revolving said crankshafts, and doors forming the outer side of said compartment.

JOHN N. GROSS.
